United States Patent Office

Des. 202,933
Patented Nov. 16, 1965

202,933

BOTTLE

Richard L. Platte, Ann Arbor, Mich., assignor to Hoover
Ball and Bearing Company, Saline, Mich.

Filed Feb. 23, 1965, Ser. No. 83,930

Term of patent 14 years

(Cl. D58—6)

FIG. 1

FIG. 2

FIG. 3

I claim:

The ornamental design for a bottle, as shown.
